*Primary Examiner—Holly Baynham***Attorney, Agent, or Firm—Michael J. Kline; Carol I. Bordas****[57] CLAIM**

The ornamental design for a humidifier, as shown and described.

DESCRIPTION

FIG. 1 is a top right front perspective view of a humidifier showing my new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof;

FIG. 7 is a bottom plan view thereof;

FIG. 8 is a top right front perspective view of a second alternate embodiment of my humidifier; the rear elevational view, right side elevational view and left side elevational view being the same as the corresponding views of my humidifier shown in FIG. 1;

FIG. 9 is a top plan view thereof;

FIG. 10 is a front elevational view thereof; and,

FIG. 11 is a bottom plan view thereof.
